UNITED STATES PATENT OFFICE.

HERBERT S. ATKINSON, OF EAST ORANGE, NEW JERSEY, ASSIGNOR TO THE HAYWARD COMPANY, OF NEW YORK, N. Y., A CORPORATION OF NEW YORK.

BUCKET.

1,249,298.

Specification of Letters Patent. Patented Dec. 11, 1917.

Application filed May 23, 1913. Serial No. 769,378.

To all whom it may concern:

Be it known that I, HERBERT S. ATKINSON, a citizen of the United States, and residing at East Orange, in the county of 5 Essex and State of New Jersey, have invented certain new and useful Improvements in Buckets, of which the following is a full, clear, and exact specification, such as will enable others skilled in the art to 10 which it appertains to make and use the same.

This invention relates to hoisting buckets, and more especially to those of the type now generally known as the "clam shell."

15 One example of such bucket, and one now very largely used, is found in the patent to Herbert S. Atkinson, No. 906,184, dated December 8, 1908, in which are shown suspended from a supporting bucket head a plurality of bowl sections or segments, each of 20 the bowl sections being connected to the head by means of a pair of rods or links which oscillate back and forth as the bowl sections are opened and closed by means of 25 the rotation and raising and lowering of a power wheel. In the bucket there shown chains, suspended from the bucket head, are wrapped about the hubs of the power wheel in closing the bucket, and unwound there- 30 from in opening. These chains, as will be seen, comprise a single section or strand secured to the bucket head and a double section, or a plurality of strands, between which the single section is adapted to lie 35 35 when the chain is wrapped upon the hub of the power wheel.

In the bucket just referred to, it is very important that there be as little lateral movement of the bucket head relative to the 40 connecting rods and bowl sections and power wheel as possible, since such movement would tend to prevent the respective chain sections from alining properly whereby the single section might be permitted to over 45 lap one of the strands composing the plural section, instead of lying between the same, resulting in stress and wear upon the chains, and possible breakage. As these chains are a very important feature of the operating 50 mechanism it is essential that they be prevented from getting out of order. To prevent lateral movement of the bucket head relative to the connecting rods and bowl

sections and power wheel or vice versa, and thereby serving to keep the chain sections 55 properly alined, it has been found expedient to provide a sort of truss frame, as illustrated in the patent hereinbefore referred to, comprising for each bowl section a set of 60 two diagonal truss members, one rigidly connected to the upper portion of one of the connecting rods and both pivotally connected to approximately a common point at the center of the rear edge of the bowl section. It has also been found desirable for the same 65 reasons to provide other truss members connected at approximately the same bearing point on the bowl sections and extending diagonally therefrom, one to each of the side arms of the bowl sections. The elimination, however, of such truss members is desirable not only on account generally of the greater clearance obtained in the bucket for 70 the material to be handled but as frequently the bucket may be used for conveying or 75 transferring materials placed or thrown by manual labor into the bucket in closed position, such truss members are at such times an obstacle to the loading of the bucket.

The object of the present invention is to 80 provide a bucket of the class referred to, embodying, in its construction, elements serving the purpose for which the truss members referred to have been employed, viz. to keep the chain sections properly 85 alined, and yet retaining unobstructed the space heretofore occupied by such truss members.

A further object of my invention is to 90 provide a bucket more simple in its construction and less costly to build than buckets otherwise constructed.

All of these objects will be apparent from the following description, taken in connection with the accompanying drawings, in 95 which,—

Figure 1 is a perspective view of a bucket constructed according to our invention;

Fig. 2 is a detail elevation, with a portion removed;

Fig. 3 is a side elevation of the structure shown in Fig. 2;

Fig. 4 is an end elevation of the bucket shown in Fig. 1, but with a modification of certain features;

Fig. 5 is a detail on line 5—5 of Fig. 4;

100

105

Fig. 6 is a section on line 6—6 of Fig. 5; and

Fig. 7 is a detail elevation showing the form of operating chains.

Referring to the construction illustrated in Figs. 1, 2 and 3, B represents the entire bucket, which comprises a supporting head, indicated in whole at C, a plurality of bowl sections or segments indicated at D, D', the bowl section D being pivotally supported from the head C by a set of oscillating members or connecting rod E, E', which latter are pivotally connected to the rear edge of the bowl section at F, F'. The bowl section D' is pivotally connected at G, G' to a set of oscillating members or connecting rods H, H', which latter are rigidly connected to the supporting head C.

To the bowl sections D, D' are rigidly secured, at each side thereof, side arms I, I', J, J', pivotally mounted upon which and secured thereto by the shaft Z is a power wheel K, adapted to be actuated by a closing line K' which line is guided by an idler sheave K² mounted upon the head C. The power wheel K, at each side thereof, has a hub K³. Operating chains K⁴ are secured to said hubs and, at their upper ends, are secured to the head C. The bucket is supported, raised and lowered by means of a holding rope L attached to a pin L' mounted in the head of the bucket.

The supporting head C, which is preferably in the form of a single casting, comprises a main body portion M, horizontally apertured at M' to receive a pivot pin M², which latter also passes through the upper ends of the pivotally mounted oscillating members or connecting rods E, E'. At the upper portion of the body portion M is formed, preferably integral therewith, a housing N for the idler sheave K² hereinbefore referred to. Extending downwardly and rearwardly from the main body portion M are a set of two holding members or arms O, O'. The holding members or arms O, O' are shouldered at P, P' to afford bearing surfaces for the ends of the connecting rods H, H', said holding members and connecting rods H, H', being rigidly secured together by the rivets Q.

In Fig. 4 is embodied a modification in that the connecting rods H, H' are carried entirely up to the pivot pin M², but each is rigidly secured to one of the holding members O, O', so that the holding members and connecting rods secured thereto move as one.

A further important feature of my invention is the combined alining and rope guard frame illustrated more particularly in Figs. 1, 4 and 5, which will now be described. Upon each of the side arms J, J' is formed, at the inner side thereof, a spider R, which comprises the holding lugs R', R² and a boss R³, which holding lugs and boss are pro-

vided with channels R⁴ formed by the projecting edges R⁵. Within the respective channels R⁴ of the lugs R', R² and of the boss R³ are secured the respective ends of a plurality of arms R⁶, R⁷, R⁸, which extend from the side arms J to the side arms J', and for the most part are diagonally disposed, both to span the periphery of the power wheel K, as well as to form a truss adapted to take any lateral thrust or strains exerted thereon. At the points where said arms are disposed oppositely to the periphery of the power wheel, they are shaped at right angles thereto, to provide a holding surface for a guard shoe R⁹, which is adapted to project within the score of the power wheel K, so as to retain the rope K' in operative position. The guard frame, being rigidly connected, by means of the spiders R, with each of the side arms J, J', serves to rigidly secure said side arms to each other, and is adapted to prevent any lateral movement of one relative to the other, so that said side arms J, J' and said guard frame, in the operating movements of the bowl sections, move substantially as one, said side arms J, J' having an oscillating movement upon the pivot pin J' and said guard frame having a limited rotary movement about said pin, as an axis, coincident with the movement of said side arms.

It will be observed that, while I have dispensed with the use of truss members, such as hereinbefore referred to, and which, as already stated, occupy considerable valuable space, I have not eliminated the purposes and functions performed by those members, but have substituted other means for accomplishing the desired result, for it will be evident that the holding members O, O', either as the device is shown in Fig. 1, or as shown in Fig. 4, will take and withstand any lateral thrust of the bowl section D', acting on the connecting rods H, H', and as the side arms J, J'—upon which is supported the power wheel K—are rigidly secured to each other by the guard frame members R⁶, R⁷, R⁸, so as to make in effect a single operating element, the result will be to hold in alinement the power wheel K and operating chains K⁴.

By this construction I not only accomplish the results specified, but do so at a large saving in cost, since the supporting head and holding arms may be formed as a single casting, which is relatively inexpensive compared with the making of a number of separate parts, as in the case of the truss members heretofore used.

It will be obvious, therefore, that I have provided an improved bucket, which is very simple in its construction, which is less costly to build, which has fewer wearing parts and which dispenses with the use of truss members which interfere with the ma-

terials handled—with considerable economy in space—while at the same time securing the results and advantages heretofore accomplished by the employment of such members.

5 I desire it to be understood that I do not confine myself to the precise details of construction and arrangement of the invention herein set forth, as modification and variation may be made without departing from the spirit of the invention, as defined by the appended claims.

What I claim is:

1. In a bucket, the combination of a plurality of bowl sections, side arms on said bowl sections, oscillating connecting rods connected to said bowl sections, mechanism for opening and closing the bowl sections including a power wheel and operating chains having connection with said power wheel and operated thereby, said chains consisting of sections winding without overlapping in different transverse planes, a head casting for supporting said rods, mechanism and bowl sections, comprising a main body portion and a plurality of depending arms rigid thereon, adapted to straddle said power wheel and rigidly secured to the connecting rods of one bowl section, and means rigidly connecting the side arms of said bowl section.

2. In a bucket, the combination of a supporting head, a plurality of bowl segments, oscillating connecting rods connected thereto and to said head, bowl operating mechanism including a power wheel and operating chains therefor, the latter formed of single

and plural sections having operative connection with said head and with said power wheel, said supporting head comprising a main body portion and a plurality of arms rigid thereon and depending angularly thereto and rigidly secured to certain of said connecting rods, to prevent lateral movement of said head relative to said last named rods and said bowl operating mechanism and retain said chain sections in proper alinement.

3. In a bucket, the combination of a supporting head, a plurality of bowl segments, oscillating connecting rods connected thereto and to said head, side arms on said bowl segments, bowl operating mechanism including a power wheel and operating chains, said chains formed of single and plural sections having operative connection with said head and with said power wheel, said supporting head comprising a main body portion and depending arms rigid thereon and rigidly secured to the connecting rods of one bowl segment, and a plurality of guard arms rigidly connecting the side arms of said last named bowl segment and spanning the periphery of said power wheel, said main body portion and said depending arms and guard arms being arranged and adapted to prevent lateral movement of said head relative to said last named connecting rods and operating mechanism.

HERBERT S. ATKINSON.
